UNITED STATES PATENT OFFICE.

JOHN P. STEPPE, OF NEW YORK, N. Y., ASSIGNOR TO S. STERNAU & CO.,
OF SAME PLACE.

DESIGN FOR A WATER-PAN FOR CHAFING-DISHES.

SPECIFICATION forming part of Design No. 31,667, dated October 17, 1899.

Application filed September 11, 1899. Serial No. 730,174. Term of patent 34 years.

To all whom it may concern:

Be it known that I, JOHN P. STEPPE, a citizen of the United States, residing at New York, in the borough of Brooklyn, county of Kings, and State of New York, have invented and produced a new and original Design for Water-Pans for Chafing-Dishes, of which the following is a specification, reference being had to the accompanying drawings, forming a part thereof.

Figure 1 is a perspective view of a water-pan for chafing-dishes, showing my new design. Fig. 2 is a vertical sectional view thereof.

15 The leading or characteristic feature of my design consists in the shape or contour of the pan, the upper portion thereof being formed in the shape of a ring, from the lower edge of which the curve is regular, lending to the article the appearance of being much shallower than is really the case, the extreme upper edge being curled or turned over, feet or standards being provided on the under side of the pan and handles near the upper edge.

By reference to the drawings it will be seen 25 that the extreme upper edge of the pan is curled over, as illustrated at A, from which extends the ring B. From the lower edge of this ring the curve or contour of the pan is regular, the curve being such that the pan has 30 the appearance of being more shallow than it is in fact, this appearance being enhanced by the feet or standards C, which project from the under side of the pan.

D represents fanciful handles projecting 35 from the ring B.

Having fully described my invention, what I claim as new, and desire to secure by Letters Patent, is—

The design for a water-pan for chafing- 40 dishes, substantially as herein shown and described.

JNO. P. STEPPE.
